UNITED STATES PATENT OFFICE

2,581,952

ADJUSTABLE SHOE TREE

Henry Hauert, Guttenberg, N. J., assignor to
Fortuna Brothers, North Bergen, N. J.

Application November 3, 1949, Serial No. 125,309

2 Claims. (Cl. 12—128)

1

This invention relates to an adjustable shoe tree.

The principal object of this invention is the provision of a self-ventilating shoe tree which is readily adjustable to shoes and other articles of footwear of different lengths. It provides a one-point contact with respect to the inner sole of the shoe and a one-point contact with respect to its heel, and aside from these two points of contact, the inner sole and the heel are free from engagement with the shoe tree.

Another important object of the present invention is the provision of a shoe tree of the character described, which is exceedingly simple in its construction in a manner which is advantageous both from the point of view of its manufacturer and from the point of view of the person using it. In its simplest form, the shoe tree herein described and claimed, consists of but two parts which are adjustably movable relative to each other. One of the component parts of this shoe tree is provided with a plurality of teeth formed therein and the other component part is provided with one or more teeth situated for selective engagement with the teeth of the first mentioned part and it is by this means that the two parts may be adjusted and positioned relative to each other. One of the parts is provided with a pad for engaging the inner sole of the shoe in which the shoe tree is placed, it is provided with a second pad or portion which engages the heel, and it is provided with a third pad or portion which engages the counter. The other part of the shoe tree is situated and shaped to engage the upper, and more specifically, the toe and instep portions thereof.

The shoe tree constituting the present invention is ideally adapted for mass production methods of manufacture on plastic molding equipment. In its preferred form it comprises a pair of hollow plastic moldings, each molding consisting of two molded parts which are cemented together to conceal the enclosed hollow space. There is no real assembly problem. Many of the parts which are common to conventional shoe trees, are here lacking. For example, there are no pivots or lever arms in the present construction although it would be difficult indeed, if not impossible, to find a conventional adjustable shoe tree which does not have these elements.

Still another object of this invention is the provision of a shoe tree of the character described which is readily insertible into, and removable from, an article of footwear, irrespective of its length and its physical properties. The shoe tree

2

herein claimed may be made shorter or longer by simply sliding one of its parts relative to the other part. It may be locked in operative position at any selected length by simply allowing the teeth of its respective parts to engage each other.

Preferred forms of this invention are shown in the accompanying drawings in which:

Fig. 1 is a side view of a shoe tree made in accordance with the first form of this invention, showing it mounted within a shoe.

Fig. 2 is a sectional view taken on the line 2—2 of Fig. 1, showing that said shoe tree may have a hollow construction.

Fig. 3 is an exploded view of said shoe tree, one of the component parts thereof being shown only in part to disclose its construction.

Fig. 4 is another exploded view, taken in section on a transverse line similar to that of 2—2 of Fig. 1, showing the component parts of the shoe tree before they are assembled.

Fig. 5 is a side view, similar to that of Fig. 1, of a shoe tree made in accordance with a second form of this invention.

Fig. 6 is a bottom view thereof.

Fig. 7 is a sectional view on the line 7—7 of Fig. 5, showing that the shoe tree may be solid in construction.

Fig. 8 is a perspective view of a shoe tree made in accordance with a third form of this invention.

Referring now to the first form of this invention and to Figs 1 to 4 inclusive, it will be seen that a shoe tree 10 made in accordance therewith, comprises but two component parts: an upper part 11 and a lower part 12. Actually, each component part may be made in two hollow sections which are cemented or otherwise fastened together. Thus upper component part 11 consists of hollow sections 11a and 11b respectively and lower component part 12 consists of hollow sections 12a and 12b respectively. In the preferred form of this invention, these several hollow sections are molded of suitable plastics and then cemented together. A strong, hollow construction of excellent appearance results. It should not, however, be assumed that the present shoe tree may be made only in this manner and of this material, since it may readily be made in accordance with different methods and of other materials. Nor should it be assumed that the present shoe tree must have a hollow construction, as witness the shoe trees made in accordance with the second and third forms of this invention.

Upper member 11 is shaped at its forward end

to correspond to the shape of the toe and instep portions of the upper 15 of a shoe 16 or other article of footwear. The toe and instep portions of upper member 11 are identified in the drawing by means of the reference character 17. At its back end, upper member 11 is provided with a hook-shaped end portion 18. A channel 19 is formed in the bottom of member 11, longitudinally thereof and a downwardly extending tooth or rib 20 is formed at the bottom of said member 11, behind channel 19. This tooth or rib extends transversely of member 11. A cross bridge 21 is formed at the back end of channel 19 to close the channel, or at least to bridge it, at that point.

The lower part 12 of the shoe tree comprises an elongated member having a downwardly extending pad 30 at its forward end and a downwardly extending portion or pad 31 at its back end. Its back end also curves upwardly and then forwardly to form a horn-shaped projection 32. A plurality of teeth 33 is formed along the top edge of said lower member 12. It will be noted in Fig. 2 that channel 19 of upper member 11 is adapted to accommodate that portion of lower member 12 which projects forwardly of downwardly extending portion or pad 31. More specifically, the dimensions of said channel and of said lower member 12 are such as to enable the lower member to move longitudinally of the upper member in said channel 19. Bridge 21 serves as a retaining member to prevent dislodgement of said lower member 12 from said channel 19. The bridge does not, however, prevent a limited rocking movement of said lower member 12 in said channel 19 on a vertical plane and the forward end of said lower member 12 is rounded on its upper surface to facilitate such rocking movement.

When the lower member is mounted in the channel of the upper member and the two members are pressed together, tooth 20 enters one of the notches separating teeth 33 and thereby locks the two members against relative longitudinal movement. The overall length of the shoe tree depends upon which notch tooth 20 engages and it will be understood that any one of the notches may be selected so that the shoe tree may conform to the inside dimensions of the article of footwear into which it is to be inserted.

When the shoe tree above described is inserted into an article of footwear, pad 30 of lower member 12 engages the inner sole 40 of said article of footwear, downwardly projecting portion or pad 31 engages the heel 41 and the upwardly curved horn-shaped portion 32 engages the counter 42. The toe and instep shaped portion 17 of the upper member 11 engages the toe and instep portions 15 of the upper of said article of footwear. In other words, the tendency of upper member 11 is to press downwardly upon lower member 12 and the tendency of said lower member is to press upwardly against the upper member. The two members together provide a wedge-like effect upon the article of footwear and thereby maintain said article of footwear in properly supported and mildly stressed condition. It will be noted in Fig. 1 that the entire inner sole and heel are completely free from contact with the shoe tree except insofar as pads 30 and 31 are concerned. Since these pads are relatively small in their area of contact with said inner sole and heel, in practical effect virtually the entire inner sole and heel are exposed to the air and adequate ventilation thereof is achieved.

Hook-shaped portion 18 of upper member 11 may very conveniently be grasped either to adjust the shoe tree in the article of footwear or to remove it therefrom. It has been stated that the two members comprising the shoe tree may be rocked, to a limited extent, relative to each other. It is therefore possible to rock the upper member 11 in clockwise direction, as viewed in Fig. 1, by simply grasping hook-shaped portion 18 and pulling upwardly, while at the same time holding the article of footwear and the lower member 12 down. The effect of this action is to free tooth 20 from teeth 33 and to make it possible to move the two members 11 and 12 longitudinally of each other. The shoe tree may thereby be lengthened or shortened, as desired, and may also thereby be removed from the article of footwear. When it is lengthened and wedged into the forward end of the said article of footwear, the effect is to cause the upper member 11 to rock, so to speak, in counter-clockwise direction, thereby causing tooth 20 to engage one of the spaces or notches separating teeth 33. The shoe tree is now locked in position.

The shoe tree shown in Figs. 5, 6 and 7 is similar in principle to the shoe tree first above described. It is, however, made of solid material, such as wood, as Fig. 7 clearly shows. Bridge 50 may comprise a metal plate which is screwed to the upper member 51 of said shoe tree. Tooth 53 may consist of another metal plate which is press fitted into a transverse slot formed in said upper member 51. Lower member 54 may be similar to lower member 12 above described except that it is solid in construction rather than hollow. In all other important respects, the present shoe tree is similar to the shoe tree first above described.

Shoe tree 55 shown in Fig. 8 is similar to the shoe tree shown in Figs. 5, 6 and 7 except that instead of having only a single tooth, upper member 56 has a plurality of teeth 57 which are adapted to engage a plurality of teeth 58 formed in lower member 59. Also, it will be noted, that the shape of teeth 57 and 58 differs from the shape of teeth 33 of the first form of this invention and the corresponding teeth of the second form. The advantage of providing a plurality of teeth both on the upper member and on the lower member of the shoe tree resides in the fact that a wider range of adjustments may thereby be had.

It will be observed from the foregoing that a highly satisfactory and efficient shoe tree is herein disclosed. In effect it consists only of two members which are adjustable relative to each other. The inner sole engaging pad, and also the heel engaging portion of the lower member provide only a minimum of contact between the shoe tree and the inner sole and heel portions of any article of foot wear into which the shoe tree may be inserted. Only two elements are provided for preventing dislodgement of the lower member from the channel of the upper member: one is the bridge across the channel of the upper member and the other is the downwardly extending pad of the lower member. These are features of great importance but it should not be assumed that the manner in which these features are executed in the three forms of the invention shown in the drawing, is limitative of said invention. Instead, these forms of the invention are merely preferred illustrations thereof and modifications may be incorporated

therein within the broad scope and spirit of the invention.

I claim:

1. A shoe tree comprising two relatively adjustable shoe-engaging members, one of said members being situated above the other member and having a longitudinal channel formed therein to accommodate the forward end of said other member in slideable relation thereto and to guide the longitudinal movements of the two members relative to each other, the upper member having a downwardly extending tooth and the lower member having a plurality of upwardly extending teeth situated for engagement with the downwardly extending tooth of the upper member for adjustably fixing the relative positions of said upper and lower members, the upper member being supported by the lower member so as to engage only the toe and instep portions of the upper of the shoe into which said shoe tree is inserted, the lower member being provided with a small downwardly extending pad at its forward end which engages the insole of the shoe, a downwardly curved portion at its back end which engages the heel of the shoe, and a backwardly curved portion on its back end which engages the counter of the shoe.

2. A shoe tree in accordance with claim 1, wherein the upper shoe-engaging member has a downwardly curved, finger-engageable hook at its back end and the lower shoe-engaging member has an upwardly curved finger-engageable hook at its back end, so that the two members may be moved relatively to each other.

HENRY HAUERT.
